CHARLES J. VILLELLA, OF EMPORIUM, PENNSYLVANIA

TESTING OUTFIT

Application filed July 9, 1930. Serial No. 466,836.

This invention relates to new and useful improvements in testing devices for electrical circuits and more particularly to a novel tester for railway signal blocks whereby workmen on the railway can ascertain the presence of trains in the blocks in which they are working.

The principal object of the invention is to provide a testing device of a portable nature, capable of being carried handily from place to place.

These and other important objects and advantages of the invention will readily become apparent to the reader.

In the drawings:—

Figure 1 represents an end elevation of the case in which the outfit is to be housed.

Fig. 2 represents a side elevational view of the case in which the outfit is to be housed.

Fig. 3 represents a view disclosing the electrical connection between the electrical devices involved and their relation when connected to rails of a trackway.

Referring to the drawings wherein like numerals designate parts, it can be seen that A refers to a trackway including the rails B and C, the rail sections being connected together in the usual manner by electrical ties.

The novel testing outfit includes a battery 5 and an annunciator 6, clips 7 and a relay generally referred to by numeral 8. This relay includes the base 9, the coil 10, the armature 11, the contact 12, and the spring 13 for normally maintaining the armature 11 away from the coil 10 and spaced from the contact 12. The coil circuit 14 includes the clips 7 and when these clips are connected across the trackway in the manner shown in Fig. 3, the outfit will be ready for operation.

When a train enters the block and bridges the rails, the coil circuit will be completed, resulting in the energization of the coil and the attraction of the armature 11. As is shown in Fig. 3, one side of the bell or annunciator 6 is connected to the armature 11, while the other side is connected to the contact 12, the connection between the last-mentioned side of the annunciator and the contacts 12 including the switch 15, and the aforementioned battery 5.

Therefore, when the armature 11 contacts with the contact 12, the annunciator circuit will be closed, resulting in the energization of the annunciator, warning the workmen that a train is moving in the block.

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:—

A portable workman's testing outfit for railroad signal and gate blocks comprising 65 an annunciator circuit including an alarm, a source of current in the annunciator circuit, a relay including a pair of contacts normally spaced apart and serving to maintain the circuit broken, said relay including a 70 coil, a lead extending from each end of the coil, and a connector on the other end of each lead, for detachable connection to a rail of a trackway.

In testimony whereof I affix my signature. 75
CHARLES J. VILLELLA.
